UNITED STATES PATENT OFFICE

ARTHUR E. SMALL, OF CHICAGO, ILLINOIS, ASSIGNOR TO UNION METAL PRODUCTS COMPANY, OF CHICAGO, ILLINOIS, A CORPORATION OF DELAWARE

METAL STRUCTURE FOR RAILWAY CARS

Original application filed October 19, 1922, Serial No. 595,634. Patent No. 1,681,811, dated August 21, 1928. Divided and this application filed February 18, 1928. Serial No. 255,450.

My invention relates to the construction of railway cars, and more particularly to metal end structures or walls for railway cars made of one or more metallic plates or panels 5 formed with integral reinforcing, stiffening and bracing embossments or corrugations. However, this device may be incorporated in the construction of car side walls, floors, roofs or doors used in connection with railway cars 10 of various types.

It is well known that the end walls of railway cars are more likely to be broken or otherwise injured than the side walls. This is due to the inertia thrusts and pressures caused by 15 the shifting of the cargoes when the train starts or stops. These thrusts may be local, tending to distort the end in some particular spot, as, for example, when a piece of piping or lumber shifts lengthwise imparting a blow 20 against the end wall of the car; or there may be a general tendency to break out the end wall as a whole or tear it away from the framing. For the purpose, therefore, of greater 25 strength and durability, car ends have been constructed of metal plates corrugated or formed with ribs to impart the desired strength, rigidity and resiliency.

One of the principal objects of my invention is to provide a corrugated or embossed 30 metallic end structure for railway cars in which the corrugations or embossments have a configuration and arrangement that impart to the structure a maximum capacity for resisting cargo thrusts, both local and general, 35 static or quiescent, and with sufficient resiliency to prevent permanent distortion due to the thrusts of the loads, with a minimum weight of metal. It is important that structures of this sort should be as light as is possible, consistent with strength and durability, 40 both for reasons of economy in manufacturing cost and also to keep the weight of the car at a minimum.

45 A further object is to provide a corrugated metallic wall element that is practically possible to manufacture. A further object is to provide a metallic wall element with corrugations or embossments that resist to a greater degree torsional stresses, as well as brace the

element, and the car end against diagonal side thrusts or weaving.

Another object is to form a metallic plate with integral corrugations or embossments which impart to it a certain amount of 55 strength and rigidity to resist loads imposed thereon and to so form the ends of the corrugations or embossments as to provide a certain amount of resiliency to enable the plate to deflect and return to its normal position 60 without appreciable amount of permanent distortion.

In the drawings:

Fig. 1 is an end elevation of a car equipped 65 with my invention.

Fig. 2 is a section on line 2—2 of Fig. 1.

Fig. 3 is a front view of a corrugated plate.

Fig. 4 is a top view of Fig. 3.

Fig. 5 is a section on line 5—5 of Fig. 3.

Fig. 6 is a section on line 6—6 of Fig. 3. 70

Fig. 7 is a section on line 7—7 of Fig. 3.

Fig. 8 is an enlarged section of a portion of the plate on line 5—5 of Fig. 3.

Fig. 9 is an enlarged section of a portion of the plate on line 6—6 of Fig. 3. 75

Fig. 10 is an enlarged section of a portion of the plate on line 7—7 of Fig. 3.

Like characters of reference designate like parts.

Referring to Figs. 1 and 2. The corrugated or embossed plates or panels 1, 2 and 3 extend across the car from side to side and are formed with integral flanges 4 along the vertical edges which overlap and are secured to the frame members of the side walls 5 of the car by any suitable means. The top edge of the end wall is secured beneath the fascia boards 7 and the meeting edges of the plate overlap and are secured together by rows of rivets 8 and the lower edge of the end wall is 85 secured to the end sill 9. Nailing strips 10 are secured to the plates 1, 2 and 3 by bolts and lining 11 is secured to the nailing strips 10.

While the corrugations or embossments are 95 shown pressed outwardly from the original plane of the plate and in horizontal arrangement, it is understood that the corrugations or embossments may be pressed inwardly or partially inwardly and partially outwardly 100

from the original plane of the plate, or the corrugations or embossments may be placed in any position; for instance, vertically or horizontally. The plates or panels may be applied to any type of railway car.

5 Figs. 3 to 10 inclusive show the preferred form wherein the plate is provided with a plurality of parallel corrugations or embossments, each embossment preferably comprising a plurality of relatively shallow sinuous minor corrugations 20 formed therein which are spaced apart distances substantially equal to their respective widths and the part 21 of the plate between adjacent minor corrugations is also sinuous so that these minor corrugations merge together to form a contiguous sinuous configuration (see Fig 7) symmetrical in cross section about a line midway between the outermost portions of these minor corrugations so that this line is the neutral axis of the section. Such a section is very resilient and has a spring like action under loads, and, furthermore, produces a very strong section for the amount of metal used. These minor corrugations merge into the plane of the plate by means of terminal portions 22 of any desired formation. A plurality (two or more) of such minor corrugations 20 merge together between their opposite ends to form a plurality of fewer relatively deep major corrugations 23 with arcuate apices which are spaced apart distances substantially equal to their respective widths and the part 24 of the plate between these major corrugations is also arcuate, thus forming a configuration (see Fig 5) symmetrical in cross section about a line midway between the outermost portions of these major corrugations so that this line is the neutral axis of the section. Such a section (see Fig 5) is stronger and relatively rigid as compared with the section of the sinuous minor corrugations or embossments (see Fig. 7) because more metal is positioned away from the neutral axis and the increased depth also increases the strength of the beam. The arcuate apices of the major corrugations 23 and the arcuate part 24 of the plate function as arches to transmit any load imposed thereon to the opposite walls 26-27 of the major corrugations.

By such an arrangement a corrugated metallic plate is provided which is relatively rigid between the opposite ends of the corrugations or embossments and relatively resilient adjacent the opposite ends of the corrugations or embossments. The secondary oppositely projecting rib 25 formed by the merging of the two adjacent minor corrugations 20 is equal in width to the adjacent minor corrugations at 28 and decreases in width as the minor corrugations 20 merge together to form the major corrugations 23. These secondary oppositely projecting ribs 25 also preferably decrease in depth so that any con-

centrated stretch of metal is eliminated where the minor corrugations merge together.

As the embossment increases in depth toward its middle portion, this secondary rib preferably decreases in depth proportionately so that the lengths of the center lines of the metal of all cross sections of the embossment are equal to each other.

I have designed my invention for use in steel plates so that when the section modulus of my section (normal to the corrugations or embossments) is multiplied by a constant fibre stress the result equals the bending moment of that section for either a load concentrated at the middle of the beam-corrugations or for a load equally distributed over the beam-corrugations, thus showing that I have not sacrificed any required strength at the ends of the beams to obtain resiliency; in other words, by my construction I obtain a very strong beam which is also resilient. The major corrugations are preferably wider than the minor corrugations.

These shallower and deeper corrugations or embossments may be positioned and dimensioned so that the length of the center line of the metal of a cross section of the shallower corrugations or embossments (see Fig. 7) is the same as the length of the center line of the metal of a cross section of the deeper corrugations or embossments (see Fig. 5), and, furthermore, the corrugated plate may be so formed that the length of the center line of the metal of any cross section (for instance, as per Fig. 6), is equal to the length of the center line of the metal of any other cross section, that is, between the terminal portions. This is a material manufacturing advantage as it more evenly distributes the draw and stretch of the metal due to pressing the corrugations or embossments in the plate.

Plates provided with a plurality of contiguous narrow corrugations possess a considerable amount of elasticity and when struck a blow deflect readily and regain their shape without distortion, whereas a plate provided with wide arcuate corrugations, though better able to carry quiescent loads, has not the resiliency of the former and is more readily distorted when struck a blow.

It is, therefore, desirable to design a plate that possesses great strength to withstand the sudden impact load blow with sufficient resiliency to resist distortion.

The drawings illustrate the preferred form of the invention, though it is to be understood that the invention is not limited to the exact details of construction shown and described, as it is obvious that various modifications thereof within the scope of the claims will occur to persons skilled in the art.

This is a division of my co-pending application Serial No. 595,634, filed October 19, 1922; patented August 21, 1928, No. 1,681,811.

I claim:

portions, said embossments merging together between their opposite ends to form a plurality of fewer wider and deeper embossments spaced apart distances substantially equal to 5 their width having arcuate apices with the parts of the plate between the embossments also of arcuate configuration, said embossments and said parts forming a cross section symmetrical about a line midway between 10 their outermost portions.

the parts of the plate between said corrugations also of arcuate configuration, said corrugations merging together between their ends to form a plurality of fewer corrugations having arcuate apices with the parts of 70 the plate between the last mentioned corrugations also being arcuate, said corrugations terminating into the plate adjacent said oppositely disposed frame members.

ARTHUR E. SMALL. 75

14. A metallic panel for a railway car structure having a plurality of reinforcements formed therein with their longitudinal axes substantially parallel, said reinforcements and the part of the panel between them 15 being of sinuous configuration and comprising tension and compression members connected by webs, and reinforcing ribs springing from said tension members adjacent their 20 centers which gradually increase in depth toward the opposite ends of the reinforcements.

15. A metallic panel for a railway car structure having a plurality of reinforcements formed therein with their longitudinal axes substantially parallel, said reinforcements and the part of the panel between them 25 being of sinuous configuration and comprising tension and compression members connected by webs, and reinforcing ribs springing from one of said members adjacent their 30 centers which gradually increase in depth toward the opposite ends of the reinforcements.

16. A metallic panel for a railway car structure having a plurality of reinforcements formed therein with their longitudinal axes substantially parallel, said reinforcements and the part of the panel between them 35 being of sinuous configuration and comprising tension and compression members connected by webs, and reinforcing ribs springing from one of said members adjacent their 40 centers which gradually increase in depth and 45 in width toward the opposite ends of the reinforcements.

17. A wall for a railway car comprising a metallic plate secured to oppositely disposed frame members of the car, said plate provided with a plurality of sinuous embossments with the parts of the plate between the embossments also of sinuous configuration, said embossments merging together between their opposite ends to form a plurality 50 of fewer major embossments having arcuate apices with the parts of the plate between the major embossments also of arcuate configuration, said embossments terminating within the plate adjacent said oppositely 55 disposed frame members.

18. A metallic structure for a railway car comprising a metallic plate secured to oppositely disposed frame members of the structure, said plate provided with a plurality of 60 arcuate corrugations of varying depth with
